UNITED STATES PATENT OFFICE.

FRANCIS H. HOLTON, OF BROOKLYN, NEW YORK.

BUTT-CUSHION FOR FIRE-ARMS.

SPECIFICATION forming part of Letters Patent No. 240,251, dated April 19, 1881.

Application filed December 29, 1880. (No model.)

To all whom it may concern:

Be it known that I, FRANCIS H. HOLTON, a citizen of the United States, residing in the city of Brooklyn, county of Kings, and State of New York, have invented certain new and useful Improvements in Gun-Stock Butt-Cushions, fully described and represented in the following specification and the accompanying drawings, forming a part of the same.

10 My improved shoulder-guard for guns belongs to that class of such devices that consist of a case or cover capable of being secured upon the butt of the stock of a gun, so as to provide the same with an elastic cushion, whereby, when the gun is placed to the shoulder and fired, its recoil is overcome and the user suffers no shock or bruise therefrom, as is frequently the case when in certain kinds of shooting large charges of ammunition are used.

15 My invention relates more particularly to the peculiar structure of the device, the same consisting in a construction that provides a cellular formation or air-cushion that is interposed between the butt of the gun and the shoulder of the user.

20 I have illustrated in the accompanying drawings one embodiment of my invention, the structure being one of the best forms of the invention for practical purposes.

25 Figure 1 shows an elevation of the guard as applied to a gun-stock. Fig. 2 is a longitudinal sectional elevation of the guard. Fig. 3 is a transverse sectional elevation thereof; and Fig. 4 is a similar view of a modification thereof, said Figs. 3 and 4 being drawn at a reduced scale.

30 As thus illustrated, the guard consists of a case or cover, made preferably of india-rubber, in such form as to fit over the butt-end of the stock of the gun and be retained there by the elasticity of its sides A, or it may be by means of a bead-like projection, as 2, or by any mechanical means. The bottom piece, B, of this case or cover is provided on its inner surface with a number of elastic cells, which may be constructed in a variety of ways. In one form shown they consist of short lengths of rubber tubing 4, that may be secured to the bottom piece, B, either by rubber or other cement or by any well-known means of attachment. Another form shown represents a fl-form of

cell, constituted by attaching short trough-like pieces of rubber or similar material by the edges of its sides to the surface of the bottom piece, 55 B. A third form shown represents a length of tubing, coiled within itself and attached to the bottom B, so as to present a regular or even bearing-surface. It is obvious, however, that these cells may be provided by tubes or other hollow structures, arranged to run diagonally or in any other direction over the inner surface of the bottom piece, B, and still be within the scope of my invention; also, that the cells may be formed by cup-like projections 65 extending inward from said bottom piece. It will also be obvious that while rubber is a preferable material, any other substance that will provide the elastic cushion due to the cellular structure may be used.

70 The bottom piece, B, may be made much stronger and heavier than the sides, and said bottom piece may have a plain exterior surface, or be matted or otherwise roughened to prevent the gun from slipping when in use.

75 The cellular or cushioned surface may be on the outside or inside of the guard, as may be preferred.

80 A gun provided with this improved guard may be fired with very heavy charges and for any number of times without danger of bruising or jarring its user, the elastic shoulder-bearing provided by the cellular guard acting to take up the motion of recoil, and thus modifying or deadening its shock.

85 I am aware that various constructions of spring-seated butt-plates have been applied to guns, and therefore make no claim, broadly, to an elastic shoulder-guard; but

What I claim is—

90 A shoulder-guard for guns, consisting of a butt-piece, as B, provided with a number of rubber cells, each inclosing an air-space, and provided with means for securing it upon the butt-end of a gun-stock, substantially as described.

95 In testimony whereof I have hereunto set my hand in the presence of two subscribing witnesses.

F. H. HOLTON.

Witnesses:

T. H. PALMER,
Geo. H. GRAHAM.
